UNITED STATES PATENT OFFICE.

ADALBERT FISCHER, OF PHILADELPHIA, PENNSYLVANIA.

CONDENSER.

1,109,745.

Specification of Letters Patent.

Patented Sept. 8, 1914.

Application filed July 9, 1912. Serial No. 708,407.

To all whom it may concern:

Be it known that I, ADALBERT FISCHER, a subject of the German Emperor, residing at Philadelphia, county of Philadelphia, 5 and State of Pennsylvania, have invented certain new and useful Improvements in Condensers, fully described and represented in the following specification and the accompanying drawings, forming a part of 10 the same.

This invention relates to surface condensers intended especially for condensing steam but adapted also for condensing other condensable gases or vapors.

15 The object of the invention is to increase the efficiency of the condensing surfaces, and generally to provide an improved condenser of this type.

Surface condensers as commonly made, 20 having banks of pipes or tubes for the passage of the cooling water extending through the condensing chamber, have the disadvantage that the cooling action of the surface of the water tubes is interfered with 25 more or less by the water of condensation which collects thereon. If the tubes are vertical, a considerable part of the surface of each tube will, when the condenser is in operation, be covered with a film or drops 30 of water, and if the tubes are horizontal, water deposited on the upper tubes drops down on to the tubes below; and furthermore when the steam flows transversely of the tubes a portion of the condensing sur-

35 face on one side of the tubes is more or less ineffective. The present invention aims to avoid these disadvantages of the tubular surface condensers and to secure a more efficient action by providing the condenser 40

with cooling surfaces that will quickly and automatically clear themselves of the water of condensation deposited thereon and which are so arranged that the water from an upper surface will not fall on and im-

45 pair the action of a lower surface and that steam to be condensed will come into contact with all parts of the condensing surfaces. To this end I form the condenser with upwardly extending condensing sur-

50 faces, which for best results are vertical or approximately so, and divide these upwardly extending surfaces into a number of parts or portions each of which is arranged to clear itself of the water of condensation deposited on it by being separated from the portion next below it by a pro-

jecting angle or edge from which the water will be discharged, these discharging edges being arranged in different vertical planes so that the water discharged from any one 60 will fall clear of the ones below.

In the most approved form of my condenser the self-clearing condensing surfaces are provided by one or more hollow bodies or shells which are arranged vertically and 65 are of decreasing cross sectional area from the base or intake end to the top or outlet end, and which are provided at intervals around their inner condensing surface with projecting angles or edges for discharging 70 the water of condensation deposited on the condensing surface. The shells or bodies are cooled by water or other suitable cooling medium caused to flow against the outside surface of the bodies. In the form 75 which I now consider most practical, the condensing shells or hollow bodies are made up of a number of cylindrical sections of successively decreasing diameter from the lower to the upper end of the body, each 80 such section being joined to the next section above by an inwardly extending flange or shoulder with a discharging edge or angle between such flange or shoulder and the next upper section, such discharging 85 edge or angle being conveniently formed by having the bottom edge of the next upper section project downward slightly below the flange or shoulder.

A full understanding of the invention 90 and the advantages thereof can best be given by a detailed description of an approved construction embodying the same, and such a description will now be given in connection with the accompanying drawings; in 95 which—

Figure 1 is a central vertical sectional view of such a condenser; and Fig. 2 is a horizontal view partly in section on line 2 of Fig. 1 but on a reduced scale. 100

Referring to the drawings, the condenser shown has a bottom chamber 10 which serves as a receiving or inlet chamber for the steam to be condensed and the lower part of which serves as a hot well for receiving the 105 water of condensation. The steam enters the chamber through an inlet 11, and the water of condensation is pumped from the hot well through an outlet pipe 12. Extending upward from the chamber 10 are a 110 number of condensing chambers 13 formed by thin metal shells or bodies 15 of copper

or other suitable metal which are of gradually decreasing cross sectional size from their lower to their upper ends and which open at their upper ends into an air chamber 16 provided with an outlet 17. Immediately beneath the air chamber 16, is a chamber or header space 18 to which water or other cooling fluid is supplied through an inlet 19 and from which the water flows downward over the outer surface of the condensing bodies or shells 15 to a lower water chamber 20 immediately above the chamber 10 and from which the water passes away through an outlet 21. The condensing bodies or shells are shown as inclosed, and for best results should be inclosed, by jackets 22 spaced off from the condensing bodies to leave a space through which the cooling water may flow over the shells from the water chamber 18 to the chamber 20.

The side walls 23 and top wall 24 of the chamber 10 may be formed of a single casting as shown, and the bottom 25 of the chamber 10 may be formed as a separate part having a flanged or other connection with the bottom edge of the side walls 23 so as to be detachable therefrom for cleaning or other purposes. The water chambers 18 and 20 and the inclosing jackets 22 for the condensing shells may be made of a single casting 26 detachably secured by a flanged connection or otherwise to the casting forming the side and top walls of the chamber 10 as shown, and which may be open at the bottom so that the top wall 24 of the chamber 10 will form the bottom wall of the water chamber 20, and which will have a top wall 27 forming the partition between the inlet water chamber 18 and the air chamber 16, a wall 28 forming the bottom of the water chamber 18, a wall 29 forming the top of the lower water chamber 20, and the jackets 22 extending between the walls 28 and 29. The wall 28 is formed with openings 30 through which the upper ends of the condensing shells 15 pass and through which the water flows from the chamber 18 downward inside the jackets 22, and the wall 29 has openings 31 for the lower portions of the shells 15 and through which the water passes to the chamber 20. A cap piece 32 forming with the wall 27 the chamber 16 may be removably secured to the top of the casting 26.

The condensing shells 15 are supported by the horizontal walls 24 and 27 and may be secured thereto in any suitable manner, but are best secured so as to be independently removable. As shown, the lower edge of each of the shells 15 rests on an annular supporting ring 33 which is positioned and held in a threaded opening in the horizontal wall 24 by an annular exteriorly threaded nut 36. The openings in the wall 24 are formed with downwardly facing shoulders

37 against which shoulders on the supporting rings seat when the rings are forced upward and clamped in position by the nuts 36. The reduced upper ends of the condensing shells extend into flanged and shoudered ends of short sections of pipe 40 by which they are held in position, each such short pipe 40 extending through an opening in the partition 27 and being held in position in the opening by a bushing 41 to which the pipe section is secured by means of a nut 42 which screws on to the end of the pipe. The openings in the wall 27 are threaded and the bushings are flanged and threaded to make a tight closure of the opening.

Each of the condensing shells 15 in the form shown is made up of a plurality of cylindrical sections 50 which are of successively smaller diameter from the bottom to the top of the shell, and each of these sections except the uppermost one has at its upper end an inwardly extending flange 51 by which it is connected to the lower part of the next section to provide drip or discharge edges or angles between the sections. In the arrangement shown, the flange 51 of each flanged section is connected with the outside of the next upper section at a point slightly above the lower edge of such next upper section so that the lower edge of each shell section except the lowermost section will form a discharge angle or edge 52 from which the water or other liquid deposited on such section will fall into the bottom of the chamber 10 or hot well without striking or collecting on any lower cooling surface. Water deposited on the lowermost section 50 of each condensing shell will run down and fall to the hot well from the supporting ring and clamping nut at the bottom. The jackets 22 should be shaped to conform substantially to the shape of the stepped condensing bodies or shells, as shown.

In the operation of the condenser, the cooling water enters through the inlet 19 into the chamber 18 and flows downward through the openings 30 and over the outside of the condensing shells 15 in the space between said shells and the jackets 22 and is discharged from the chamber 20 through the outlet 21. Steam to be condensed enters through the inlet 11 and passes from the chamber 10 upward through the condensing chamber 13 to be cooled and condensed by contact with the walls of the condensing shells, the water of condensation falling into the hot well, and any air carried in with the steam or other uncondensed gases or vapors passes from the condensing chambers through the pipes 40 into the air chamber 16 from which it is withdrawn through the outlet 17. Water deposited on the vertically short condensing surfaces of the several

sections 50 of each condensing shell will collect at the several discharge edges 52 and fall therefrom into the hot well. Each section of the condensing surface thus quickly 5 clears itself of the water of condensation without interfering with the action of any other portion of the condensing surface, the whole aggregate condensing surface remaining free from liquid and in condition to act 10 most efficiently in cooling the adjacent steam. All parts of the condensing surface, also, will be effective since there are no parts to interfere with the free access of the steam to any portions of the condensing surface. It will be observed that because of the 15 diminishing diameters of the condensing shells from the bottom to the top, the amount of cooling surface and also the cross sectional area or size of the condensing 20 chambers decreases gradually as the amount of steam left to be condensed decreases with the upward flow of the steam toward the top of the condensing chambers. It will be observed, also, that the arrangement of the 25 condenser is such that the direction of flow of the cooling water over the condensing shells is counter to that of the flow of the steam within the shells. This counter flow 30 of the cooling agent is of great importance in a condenser and my present invention lends itself especially well to such counter current cooling. Obviously, however, the flow of the cooling water might be reversed, if desired, the water then entering through 35 the outlet 21 and being discharged through the inlet 19. It should be noted, further, that the construction of the condenser as shown and above described provides for ready access to the interior of the various 40 parts thereof, and removal and replacement of the condensing bodies or shells.

It will be understood that the invention is not to be limited to the exact construction and arrangement of parts in the particular 45 form of condenser shown in the drawings and to which the foregoing description has been largely confined, but that it includes changes and modifications thereof within the claims.

50 What is claimed is:

1. A surface condenser having an upwardly extending cooling surface divided transversely of the direction of flow of the liquid deposited thereon into a plurality of 55 sections, each section being provided with means for clearing it of liquid deposited thereon independently of the other section or sections.

2. A surface condenser having an upwardly extending cooling surface a portion of which is separated from an adjacent lower portion by a part formed to prevent liquid deposited on the portion above from flowing over such lower portion.

65 3. A surface condenser having an up-

wardly extending cooling surface separating a condensing space from a cooling liquid space, said surface being divided into a plurality of sections separated by projecting water-discharging edges formed to discharge the liquid deposited on the section above the edge and to direct it away from the section or sections below. 70

4. A surface condenser having a cooling surface formed by a vertically arranged shell which separates a condensing space within it from a space for a cooling liquid outside the shell, said shell being of decreasing cross sectional size from its inlet to its outlet end and the inner, cooling surface of the shell being divided transversely of the direction of flow of the liquid deposited thereon by means for discharging the liquid deposited on the surface above such means and directing it away from the 85 surface below. 80

5. A surface condenser having a cooling surface formed by a vertically arranged shell which separates a condensing space within it from a space for a cooling liquid outside the shell, said shell being of decreasing cross sectional size from bottom to top and the inner, cooling surface of the shell being divided horizontally into a plurality 90 of sections separated by projecting water-discharging edges formed to discharge the liquid deposited on the surface of the section above the edge and to direct it away from the surface of the section below. 95

6. A surface condenser having a cooling surface formed by a vertically arranged shell which separates a condensing space within it from a space for cooling liquid outside the shell, said shell comprising a plurality of cylindrical sections of successively smaller diameter from the lower to the upper end of the shell, said sections being joined together and having water-discharging edges separating the inner, cooling surfaces of adjacent shell sections and formed to discharge the liquid deposited on the surface of the section above the edge and to direct it away from the surface of the section below. 100 105

7. A surface condenser having a cooling surface formed by a vertically arranged shell comprising a plurality of cylindrical sections of successively smaller diameter from the lower to the upper end of the shell joined together by inwardly extending flanges, each section joined to one below having its lower edge projecting below the connecting flange to form a water-discharging edge. 110 120

8. A surface condenser comprising in combination a condensing shell which separates a condensing space within it from a space for a cooling agent outside the shell, said shell being of decreasing cross-sectional size from one end to the other, and the in- 125 130

- ner, cooling surface of said shell being divided transversely of the direction of flow of the liquid deposited thereon by means for discharging the liquid deposited on the surface above such means and directing it away from the surface below, an inlet for admitting steam to the larger end of the shell, an outlet from the small end of the shell, and means for subjecting the shell to the action of a cooling agent.
9. A surface condenser comprising in combination a vertically arranged condensing shell of decreasing cross-sectional size from bottom to top, an inlet for admitting steam to the bottom of its shell, an outlet from the top of the shell, and means for supplying a cooling liquid to flow downward over the outer surface of the shell.
10. A surface condenser comprising in combination a vertically arranged condensing shell of decreasing cross-sectional size from bottom to top, the inner cooling surface of the shell being divided by one or more projecting water-discharging edges, an inlet for admitting steam to the bottom of the shell, an outlet from the top of the shell, a jacket inclosing the shell and spaced therefrom to provide a space for the flow of a cooling agent between the jacket and the shell.
11. A surface condenser comprising in combination a steam chamber to which the steam to be condensed is admitted, an outlet from said chamber for the water of condensation, a plurality of condensing chambers formed by vertically set shells of decreasing cross-sectional size from bottom to top and open at the bottom to the steam chamber and having air outlets at the top and the inner, cooling surfaces of which shells are divided horizontally into sections by projecting water-discharging edges, and means for causing a cooling agent to flow over the outer surface of said shells.
12. A surface condenser comprising in combination a steam chamber to which the steam to be condensed is admitted, an outlet from said chamber for the water of condensation, a plurality of condensing chambers extending upward from said steam chamber formed by shells of decreasing cross-sectional size from bottom to top and having air outlets at the top, an upper water chamber having an inlet for supplying water thereto, a lower water chamber hav-

ing an outlet leading therefrom, and jackets extending between and open to said water chambers and inclosing said shells and spaced therefrom.

13. A surface condenser comprising in combination a steam chamber to which the steam to be condensed is admitted, an outlet from said chamber for the water of condensation, a plurality of condensing chambers formed by vertically set shells of decreasing diameter from bottom to top and open at the bottom to the steam chamber and the inner cooling surfaces of which are provided with projecting water-discharging edges, an air chamber into which the upper ends of the condensing shells open, an upper water chamber having an inlet for supplying water thereto and through which the upper ends of the condensing shells extend, a lower water chamber having an outlet leading therefrom and through which the lower ends of the condensing shells extend, and jackets extending between and open to said water chambers and inclosing said condensing shell and spaced therefrom.

14. A surface condenser comprising in combination a steam chamber to which the steam to be condensed is admitted, a plurality of condensing chambers formed by independently removable shells of decreasing diameter from bottom to top open at the bottom to said steam chamber, and jackets inclosing said shells and spaced therefrom to provide a space for the flow of a cooling liquid, said shells being detachably secured to the wall of the steam chamber and independently removable.

15. In a surface condenser, a supply water chamber, a discharge water chamber, a plurality of jackets connecting said chambers, a steam chamber adjacent one of said water chambers, an air chamber adjacent the other of said water chambers, and a plurality of condensing chambers formed by shells inclosed by said jackets and extending through said water chambers from the steam chamber to the air chamber.

In testimony whereof I have hereunto set my hand in the presence of two subscribing witnesses.
